DESIGN.

—o—
F. SCHMIDT.

SPOON OR FORK HANDLE.

No. 19,071.

Patented Apr. 30, 1889.

UNITED STATES PATENT OFFICE.

FREDERICK SCHMIDT, OF NORTH ATTLEBOROUGH, MASSACHUSETTS,
ASSIGNOR TO F. M. WHITING & CO., OF SAME PLACE.

DESIGN FOR A SPOON OR FORK HANDLE.

SPECIFICATION forming part of Design No. 19,071, dated April 30, 1889.

Application filed March 29, 1889. Serial No. 305,311. Term of patent 3½ years.

To all whom it may concern:

Be it known that I, FREDERICK SCHMIDT, a citizen of the United States, residing at North Attleborough, Bristol county, Massachusetts, have invented and produced a new and original Design for Forks or Spoons, of which the following is a specification.

In the accompanying photograph, illustrating my design, it is represented as applied to the handle of a spoon; but it will be understood that it may be applied to a fork with as equally good effect.

The leading feature of my design consists of a spray of oxalis on the handle of the spoon or fork, the spray including one large

leaf and several smaller leaves, the stems of all the leaves being connected, the base of the spray being toward the enlarged part of the handle. Two full-blown flowers of the plant are also shown. The leaves of the spray are 20 gracefully arranged so as to occupy the entire upper part of the handle.

What I claim is—

The design for a spoon or fork handle, consisting of a spray of oxalis, as shown.

FREDERICK SCHMIDT.
